CLAIM

The ornamental design for a display stand, as shown and described.

DESCRIPTION

FIG. 1 is a front perspective view of a display stand showing my new design.

FIG. 2 is a front elevational view thereof, the rear elevational view being a mirror image.

FIG. 3 is a top plan view thereof.

FIG. 4 is a bottom plan view thereof.

FIG. 5 is a left-side elevational view thereof, the right side elevational view being a mirror image; and,

FIG. 6 is a sectional view of the invention taken along line 6-6 in FIG. 2.

1 Claim, 6 Drawing Sheets
